UNITED STATES PATENT OFFICE.

JOHN KIEWICZ, OF BOSTON, MASSACHUSETTS, ASSIGNOR TO THE REECE BUTTON HOLE MACHINE COMPANY, OF BOSTON, MASSACHUSETTS, A CORPORATION OF MAINE.

BUTTONHOLE-SEWING MACHINE.

1,350,729.

Specification of Letters Patent. Patented Aug. 24, 1920.

Application filed August 7, 1916. Serial No. 113,444.

To all whom it may concern:

Be it known that I, JOHN KIEWICZ a citizen of the United States, residing at Boston, county of Suffolk, State of Massachusetts, 5 have invented an Improvement in Button-hole-Sewing Machines, of which the following description, in connection with the accompanying drawing, is a specification, like characters on the drawing representing like 10 parts.

This invention relates to buttonhole sewing machines and has for its object to provide a novel means for automatically feeding oil to the various parts of the device 15 that need constant lubrication.

In all buttonhole sewing machines it is now customary to oil the various parts by hand, but the difficulty with this is that operators are often careless about the matter of 20 lubrication and some of the parts that require constant lubrication do not get the attention which they need. My device is designed to obviate this difficulty by automatically supplying the lubricant to the 25 parts needing lubrication.

In order to give an understanding of my invention I have illustrated in the drawings a selected embodiment thereof which will now be described, after which the novel features 30 will be pointed out in the appended claims.

Figure 1 is a side view of a buttonhole sewing machine having my improvements applied thereto;

35 Fig. 2 is a section on substantially the line 2—2 of Fig. 1;

Fig. 3 is a sectional view through the pump employed for pumping the oil to the oil reservoir.

40 Fig. 4 is a plan view of the oil-distributing reservoir.

My invention is capable of being applied to any buttonhole sewing machine, but in order to give an understanding thereof, I 45 have illustrated it as it would be applied to a buttonhole sewing machine of the well known "Reece" type, an example of which may be found in United States Letters Patent No. 1,030,589, dated June 25, 1912, or in 50 my co-pending application Se. No. 100,124, filed May 23, 1916.

In the machine shown in the drawings, 1 indicates the frame of the machine which carries the stitch-forming mechanism and in

which is journaled the driving shaft 2 by 55 which said stitch-forming mechanism is operated. This stitch-forming mechanism includes the upper needle 3 and its reciprocating needle bar 4 and also an under thread-handling mechanism which I do not regard 60 it as necessary to illustrate herein. The needle bar 4 is reciprocated by means of a lever 5 pivotally mounted to the frame or head at 6 and connected at 7 to an arm 8 on an eccentric strap 9 which encircles an eccentric 65 10 on the shaft 2, this being one well-known way of reciprocating the needle bar. The driving shaft 2 extends through a suitable bearing 11 formed on the head of the frame and is also sustained at its outer end 70 in a bearing 12 carried by an arm 13 rising from the frame. This driving shaft not only actuates the stitch-forming mechanism, but it also controls the feed for the work. The work is clamped to a clamp plate 14 by 75 means of the usual work clamps 15 which are pivotally mounted on the clamp plate, and in the sewing machine herein illustrated the clamp plate 14 is mounted for longitudinal reciprocation in ways formed in the bed plate 80 16, such longitudinal movement of the clamp plate and work clamp giving the requisite feeding movement to the work. This longitudinal movement of the clamp plate 14 is derived from the usual feed cam 17 by 85 mechanism similar to that shown in my above-mentioned co-pending application and which comprises a slide 18 mounted to reciprocate in suitable ways in the bed plate 16 and detachably connected to the clamp 90 plate 14 by a latch 19. This slide 18 is provided with a stud or projection 20 operating in a groove in the feed cam 17, all as usual in sewing machines of this type.

The feed cam 17 is operated from the driving shaft 2 by mechanism similar to that shown in my above-mentioned co-pending application and which it is not necessary to describe in detail herein. It will be sufficient so far as the present invention is concerned to state that the driving shaft 2 has a spiral gear 21 thereon which meshes with and drives a gear 22 on a shaft 23 which extends down through the bed plate 16, said shaft 23 being operatively connected at its 95 lower end to the cam member 17 so that rotation of the shaft 23 will give the requisite feeding movement to the cam member 17.

Inasmuch as this form of driving mechanism for the cam member 17 forms no part of the present invention, I have not deemed it necessary to further illustrate it.

- 5 The shaft 2 is also shown as having a driving pulley 24 thereon and a suitable clutch actuated by a clutch sleeve 25 is employed for clutching the pulley 24 or unclutching it from the shaft.
- 10 The parts thus far described are or may be all as usual in buttonhole sewing machines of the "Reece" type and form no part of my present invention. In sewing machines of this nature it is necessary to 15 furnish proper lubrication for the mechanism actuating the needle bar 4, for the driving shaft 2, the gearing 21, 22, the clutch sleeve 25, etc., and my invention aims to provide means whereby these and any other 20 desired parts of the machine may be automatically lubricated, thus obviating any attention so far as the operator is concerned. This end is accomplished by providing an 25 oil-distributing reservoir which is situated above the parts to be lubricated and by providing novel means for distributing the oil in any desired quantity to anyone of the various parts that need lubrication. The oil-distributing reservoir is shown at 250 and 30 I have herein illustrated it as secured to the frame 1 of the machine above the shaft 2. While this reservoir may have any appropriate construction, I find it convenient to make it as an integral part of the usual 35 spool holder 27 which supports the spool 28 containing thread leading to the needle 3. This spool holder 27 is in the form of a bracket illustrated as having the reservoir 250 formed integral therewith, said reservoir being shown as cylindrical in shape 40 and as being situated directly over the shaft 2. Said holder or bracket 27 is secured to the arm 280 of the frame 1 by suitable screws 29. This oil-distributing reservoir is 45 provided with a plurality of discharge ports 30, each of which is controlled by a needle valve 31 that extends up through the reservoir and is operable from above the latter, as shown best in Fig. 2. Each needle valve 50 is illustrated as screw-threaded to the upper end of the reservoir, as at 32, and as provided with a knurled head 33 by which it may be adjusted. Situated beneath each discharge port 30 is a distributing pipe 34 55 which is shaped and positioned to deliver the oil deposited therein to one of the bearings to be lubricated. For instance, one pipe 34 is constructed to deliver the oil to the bearing 11; another pipe 34 is constructed to 60 deliver oil to the intermeshing gears 21, 22, thereby keeping them oiled; another pipe 24 can deliver oil to the bearing 12 or to the clutch sleeve 25 or to any other element which requires lubrication. These distributing pipes 34 are shown as extending

through and supported by the casing 35 which incloses the gears 21, 22, driving pulley 24, clutch sleeve 25, etc. Each distributing pipe is provided at its upper end with a flaring mouth 36 which is situated slightly 70 below the corresponding discharge port 30 so that sufficient space is afforded to observe the speed at which the oil is being fed from any discharge port. The reservoir 250 is also provided with a discharge port 37 75 that is situated over an opening 38 formed in the arm 280 and directly over the eccentric 9 and connections 7 between the eccentric strap 8 and lever 5. This discharge port 37 is controlled by a needle valve 39 80 similar to the needle valve 31. By properly adjusting the needle valves 31 and 39, the oil may be delivered to the parts to be lubricated at the required speed to furnish the desired lubrication, and when the valves 85 are once adjusted, no further attention on the part of the operator is required.

I have herein illustrated the distributing pipes as leading to the parts mounted on the driving shaft 2 only, but it will be obvious that additional distributing pipes 34 90 might be used leading to any other parts of the machine where constant lubrication is desired.

My invention also comprehends means for 95 automatically maintaining a supply of oil or other lubricant in the reservoir 250. This is provided for by means of a pump actuated by some moving part of the machine which pumps oil from a source of supply into the 100 reservoir 250 as long as the machine is running.

40 indicates a pump which is shown as secured to the frame 1 of the machine. This pump comprises a cylinder 41 in which 10 operates a piston or plunger 42, said cylinder having an inlet port 43 which is controlled by an inwardly-opening check valve 44. The cylinder is also provided with a discharge port 45 controlled by the outwardly-opening check valve 46 and leading into a chamber 47 which communicates with a pipe 48. The pipe 48 leads into the distributing chamber 250. The inlet port 43 communicates with a pipe 49 which leads to 11 the source of supply.

In the present embodiment of my invention I have shown a construction wherein a constant circulation of oil is maintained, the surplus oil which drips from the bearings 12 being collected in a collecting chamber and then pumped from this chamber into the reservoir 250. The machine rests on a base or support 50 as usual in sewing machines of this type, and this base in turn rests on a pan member 51 having the afore-mentioned oil well or collecting chamber formed therein, said chamber being indicated at 52. The pipe 49 leads into the oil well 52 so that the oil which accumulates in the oil well is 13

returned to the reservoir 250 by the pump. 53 indicates a screen which covers the oil well to prevent any sediment from accumulating therein. The pump 40 may be operated by any suitable moving part of the machine. I have shown it as actuated from the slide 18 so that the pump will receive one complete reciprocation during the operation of each buttonhole. The plunger 42 of the 10 pump is provided with a groove 54 in which is received the forked end of the arm 55 of an elbow lever, the other arm 56 of said lever extending down through the bed plate and being situated between two projections 57 15 formed on the slide 18 so that as said slide reciprocates, the elbow-lever 55, 56 will be oscillated thereby operating the pump.

The reservoir 250 is provided with a filling opening 58 through which oil may be 20 introduced into the chamber if desired.

While I have illustrated herein a construction for oiling certain parts of the machine, yet it will be obvious that by simply increasing the number of distributing pipes 34 and 25 locating them in proper positions, any other parts of the machine may be lubricated.

I claim:

1. In a sewing machine, the combination 30 with a frame having an upright portion and an overhanging arm, of stitch-forming mechanism carried by the frame, a driving

shaft for the stitch-forming mechanism journaled in said upright portion and extending laterally beyond the same, said frame having an opening above the portion 35 of the shaft journaled therein, an oil reservoir mounted on the top of said upright portion and provided with a boss entering and fitting said opening, said reservoir being situated directly above and parallel to said 40 shaft and extending beyond the upright portion of the frame, a plurality of ports in said reservoir, one of which extends through said boss, valves for said ports, and pipes leading from said ports to different points 45 along said shaft.

2. In a buttonhole sewing machine, the combination with a frame carrying stitch-forming mechanism, of a work clamp, means for actuating the work clamp to feed the 50 work, operating means for the stitch-forming mechanism, an oil reservoir situated above said operating means, means to deliver oil from said reservoir to the operating means to lubricate the same, a pump secured 55 to said frame, and means actuated by the work-clamp-feeding means to operate the pump.

In testimony whereof, I have signed my name to this specification.

JOHN KIEWICZ.
